UNITED STATES PATENT OFFICE.

MEINDERD S. NAP, OF HOLLAND, MICHIGAN.

MOLDING-MACHINE.

1,273,649.

Specification of Letters Patent. Patented July 23, 1918.

Application filed February 2, 1917. Serial No. 146,232.

To all whom it may concern:

Be it known that I, MEINDERD S. NAP, a subject of the Queen of the Netherlands, and resident of Holland, in the county of 5 Ottawa and State of Michigan, have invented certain new and useful Improvements in Molding-Machines, of which the following is a specification.

This invention relates to molding apparatus.

The dominant object of the invention is to provide an improved molding apparatus especially adapted for use in sand molding operations, whereby, the sand containing 15 flask can be readily and properly shifted to various positions, in order that the molding process will be expedited in general.

It is also an object of the invention and one of equal importance to provide a sand 20 containing flask which can be used to form each section or portion of a plurality of sand molds varying in size and design, thereby, eliminating the necessity of the usual cope and other similar molding appliances commonly employed in conjunction 25 with the conventional type of foundry flasks.

Another object of the invention is to provide a novel closure or follower board for 30 the flask and means on the flask engageable with the follower board for maintaining the same in positive engagement therewith during the forming of the sand mold or molds therein.

35 Another object of the invention is to provide means for retaining the molding sand in a consistent body after the design of the pattern has been formed therein and the sand mold removed from the flask, the said 40 means preventing the sagging of any portion of the sand mold when removed from the flask, thus, insuring an exact or true reproduction of the molding pattern.

Yet another object of the invention is to 45 provide the sand containing or receiving flask with tapping means which can be operated when the tamping of the molding sand about the pattern has been completed, to loosen the sand mold within the flask to 50 allow uninterrupted removal of the same.

Further, the invention aims to provide means whereby the positioning of the sand containing flask may be changed to permit the arranging of the pattern within the

same, the placing of the molding sand 55 therein and the removal of the completed sand mold therefrom.

The invention also comprehends a supporting table for receiving the flask thereon during the molding process; to receive the 60 molding pattern thereon to facilitate removal of the same from the molding flask subsequent to the tamping of the sand thereabout; and to receive the sand mold when the same is removed from the flask completed 65 and ready for the pouring operation, the table being capable of adjustment with relation to the flask to allow the sand mold to be completely removed therefrom.

A still further object of the invention is 70 to provide adjustable means for supporting the table, which means may be moved laterally in order that the tables varying in size and shape may be substituted to accommodate molds of different designs and sizes. 75

Another important feature of the present invention resides in the provision of a portable carriage for supporting the improved molding apparatus so that the same may be ported to various places during the 80 molding operation, and as a consequence, obviating the necessity of handling the heavy and cumbersome molding elements as well as the articles molded thereby.

Other objects relate to consideration of 85 economy of production, durability in use, and convenience in operation of the several mechanisms or parts entering into the construction of elements and the above defined general organization of said elements. 90

As hereinafter pointed out in the claims, some of the novel features of the present invention reside in certain co-operative relationships existing between certain of the elements, of which the disclosed constructional 95 embodiments are merely illustrative rather than definitive, while other novel features reside in the general organization of such elements, and still others reside in the constructional characteristics of the particular 100 embodiments herein disclosed as the preferred instrumentalities through which to realize such co-operative relationships and general organizations.

One embodiment of the subject matter of 105 the specification is shown by way of illustration in the accompanying drawings, in which:

Figure 1 is a side elevation of the improved molding apparatus;

Fig. 2 is a top plan thereof;

Fig. 3 is an end elevation of the same;

5 Fig. 4 is a vertical section in elevation taken through the improved molding flask;

Fig. 5 is a fragmentary detail partly in section showing the connection of the table elevating and lowering means with the operating means therefor;

10 Fig. 6 is a detail in section taken on the line 6—6 of Fig. 3; and

Fig. 7 is a fragmentary detail in section of the mounting of the molding flask elevating and lowering means.

Similar characters of reference are employed in all of the above described views to indicate corresponding parts.

Referring now more specifically to the several figures of the said drawings, there is provided a carriage designated in its entirety by the numeral 1, the said carriage member comprising a plurality of longitudinally arranged parallel side bars 2, 25 transversely disposed end bars having the opposite ends thereof connected to the said side bars in proximity to their respective end portions and a plurality of flanged wheels, generally indicated by the numeral 3, the said wheels being of course mounted upon suitable axles as arranged upon the said transversely disposed bars. A track-way 4 is provided and is adapted to receive the flanged wheels 3 of the carriage 1, thereupon, whereby the improved molding apparatus, which will be hereinafter more fully described, may be ported from place to place during the molding process.

A plurality of vertically disposed standards 5 having offset feet 6 formed upon the lower extremities thereof are arranged within suitable seats as formed upon the upper faces of the side bars 2 at points in proximity to certain of the ends thereof. 45 To secure the standards 5 in position within their respective seats upon the side bars 2, set screws, connecting bolts or the like 7 are passed through suitably disposed apertures as formed within the feet 6 into engagement with the side bars 2. Laterally disposed supporting arms 8 are formed integral with the upper ends of the standards 5 and support therebetween a squared sleeve 9, which sleeve is provided with a plurality 55 of spaced apart screw threaded openings into which set screws 10 may be turned. Slidable carriages 11 are arranged upon the laterally disposed supporting arms 8 and have formed therein, preferably intermediate the side portions thereof, elongated slots 12, the said slots receiving therethrough the upper extremities of bolts 13 immovably engaged with the opposite extremities of said lateral bearing arms and having turned 60 into engagement with the screw threaded

upper extremities of locking nuts 14, whereby the same may be maintained in various adjusted positions.

Pairs of oppositely disposed vertically arranged guide elements 15 are carried upon the upper faces of the carriages 11 and are adapted to be engaged with pairs of longitudinally disposed slots or ways as formed within the opposite side portions of a table 16, the said slots or ways being designated 75 by the numeral 17. By so engaging the guide element 15 with the ways 17, it will be appreciated, that accidental displacement of the table from the carriage 11 will be prevented. It is to be noted, that the upper extremities of the guide elements 15 extend for a distance above the upper face of the table member 16, the purpose of which will be subsequently obvious. A depending squared shank 18 is affixed to the under face 80 of the table 16 at a point, preferably, concentrically thereof and is slidably received within the squared sleeve 9 carried between the lateral supporting arms 8. Upon the lower extremity of the squared shank 18, there is arranged a pair of oppositely disposed laterally extending fingers 19, which fingers are engaged by means for elevating and lowering the table 16, which means will be hereinafter more fully described. Obviously, by mounting the table 16 upon the squared shank 18, the same may be adjusted 90 vertically to suit various conditions.

Referring now to the novel molding flask, I employ a receptacle, substantially square in cross section and indicated by the numeral 20, the said receptacle having beveled side and end walls whereby the molding sand as placed therein may be readily 100 tamped or compressed into a consistent body to facilitate the molding operation. A follower board 21 is provided and is of a size and shape complementary to the larger end of the molding flask 20, the said follower board being provided with beveled side and 105 end pieces to correspond with the side and end walls of the molding flask 20. Suitable bracing bars 22 may be and preferably are arranged on the follower board 21, serving for an obvious purpose. It is to be noted, that the upper and lower marginal edges of the molding flask 20 are flanged or thickened as at 23 while the lower edges of the side and end pieces of the follower board are similarly flanged as at 24, whereby, to permit proper engagement of the same with the molding flask 20, during the molding process. Upon the flanges 23 formed upon the larger end of the molding flask 20, there is slidably arranged a plurality of plates, 115 generally designated by the numeral 25, the said plates being of a length corresponding to the length and width of the flask 20 and also being secured to the said flanges 23 for sliding movement by means of a plurality 120

of fingers 26 received within elongated slots 27 formed in the said slidable plates 25. These sliding plates 25 serve as means for retaining the sand mold within the flask 20 upon temporary removal of the follower board 21, whereby, the pattern, which will be subsequently described, may be removed therefrom.

A pattern 28 of any suitable design or 10 formation is provided and instead of being arranged upon the usual drag plate in order that the same may be properly supported within the molding flask 20, it is provided with a plurality of laterally extending flanges 15 29, the said flanges being of a width sufficient to permit the same to rest upon the slidable plates 25 and to lie adjacent the flanges 24 formed upon the beveled side and end pieces of the follower board 21. A plurality of 20 depending fingers or pins 30 are arranged upon one side of the flanges 29 and are received through suitably formed openings 31 in the follower board 21. Thus, it will be understood, that lateral movement of the 25 pattern 28 with relation to the molding flask 20 will be prevented and as a consequence, a proper and true reproduction of the said pattern will be permitted in the molding sand.

30 With a view toward providing means whereby the follower board 21 may be securely maintained in proper position upon the proper end of the molding flask 20, a plurality of oppositely disposed bifurcated 35 lugs 32 are affixed to certain of the side portions of the said molding flask 20 and pivotally receive therebetween as at 33, catch arms 34, the said arms being provided with suitable handle pieces 35 whereby the same 40 may be moved into and out of engagement with the follower board 21 when it is desired to secure the same in position or remove the same from the molding flask 20.

When the pattern 28 has been properly 45 arranged within the molding flask 20 and the follower board 21 has been clamped into engagement therewith by reason of the catch arms 34, sand is placed within the molding flask 20 and is tamped about the 50 pattern 28, whereupon, a screen 36 is placed thereover and a second layer of sand then applied over the said screen until the flask 20 has been entirely filled. By arranging the screen 36 within the molding sand, which 55 I shall indicate for the purpose of convenience by the letter S, means are provided whereby the said sand when removed from the flask 20 as a consistent body will be prevented from crumbling or allowing a portion 60 of the design of the pattern 28 as formed therein to vary or sag in anyway. Thus, an exact and true reproduction of the pattern is at all times insured. To facilitate the pouring of the molten metal, 65 after the sand mold has been properly

formed, there is arranged upon certain of the flanges 29 a vertically disposed finger 37, which finger is of height to approximately correspond to the depth of the sand molding flask 20. Consequently, when the 70

pattern is removed from engagement with the flask 20, the finger 37 will be withdrawn, leaving a channel or pouring opening communicating with the design formed in the sand by engagement of the pattern 28 therewith. Horizontally alined bearings 38 are affixed to the opposite bevel side portions of the molding flask 20 and loosely receive therein, means for elevating and lowering the said flask during the molding operation, 80 which means will be subsequently described. To insure proper turning of the flask 20 by means of the elevating and lowering means above mentioned, there is arranged upon one beveled side portion thereof, a plurality 85 of bifurcated supporting arms 39, said arms having journaled in said bifurcated portions rollers 40, whereby to permit sliding engagement of the molding flask with the upper face of the table 16 during the turning of the same. A plurality of hammers 41 are secured to certain of the side portions of the molding flask 20 through the medium of spring arms 42, these arms in turn being secured to the said side portions of the mold 90

by means of rivets or other similar fastening devices. By mounting the hammers 41 upon the spring arms 42, it will be readily understood that the same may be drawn away from the sides of the molding flask 100 20 and then released, whereupon, they will be abruptly forced into contact with the said sides by reason of the spring arms 42. Hence, the sand mold as arranged within the flask 20 may be readily loosened from 105 the side walls thereof when it is desired to remove the same. Referring now to the means for elevating and lowering the flask 20 during the molding operation, a plurality of vertically disposed bearing pillars 43 110 having offset feet 44 formed upon the lower extremities thereof are arranged at opposite points upon the side bars 2 of the carriage 1, the said offset feet 44 being received within complementally formed recesses or 115 seats in the side bars, and secured in position therein by means of set screws 45 passing through suitably arranged openings therein into engagement with the said side bars. In mounting the bearing pillars 43 upon the side bars 2 of the carriage 1, the same are preferably arranged substantially intermediate their ends, although, it will be understood that the same may be located at various points throughout the length 120 thereof, such as conditions or preference may dictate. The upper extremities of the bearing pillars 43 are provided with vertically disposed reduced portions 46, which portions have slidably engaged therewith 125

130

journal boxes 47. To secure the journal boxes 47 in fixed relation to the vertically disposed reduced portions 46, set screws 48 are turned through the upper portions 5 thereof and have their lower extremities bearing upon the upper edges of the said extensions 46. Thus, by turning the set screws 48 in the desired direction, the journal boxes 47 may be either raised or lowered 10 with respect to their respective extensions 46 to the desired position. It of course, will be understood that suitable bearing openings are formed within the journal boxes 47 and that to permit the introduction of a shaft 15 thereinto, the extensions 46 must be necessarily provided with vertically disposed elongated slots. In addition to the set screws 48 which are turned into engagement with the top portions of the journal boxes 20 47, other set screws 49 are turned into engagement with suitably arranged openings formed in the sides of the said journal boxes and are adapted to bear upon the adjacent faces of the extensions 46, thereby, preventing rattling of the journal boxes; the said set screws being designated by the numeral 49.

A transversely disposed shaft 50 having the opposite extremities thereof reduced as 30 at 51 is arranged upon the carriage 1 and has the said reduced extremities 51 rotatably mounted within the bearing openings formed in the journal boxes 47. As shown in the Fig. 7, the extremities 51 of the transverse 35 shaft 50 extend beyond the bearing openings within the journal boxes 47 and are engaged with suitable anti-frictional bearing means 52, which means are secured to the outer faces of the journal boxes 47 by means 40 of set screws 53 or the like. A segmental gear 54 is keyed upon the transverse shaft 50, preferably, intermediate the ends thereof and extends longitudinally of the said carriage to a point in proximity to one of the 45 ends thereof. Engaged with the sides of the segmental gear 54 are a plurality of angularly disposed arms 55, the said arms being provided with suitable bearing openings whereby they may be arranged over the 50 transverse shaft 50. The said angularly disposed arms 55 are provided with, substantially intermediate their ends, offset portions 55 and have formed upon their outer or free extremities bearings 57, which bearings receive therein stub-axles 58, the opposite extremities of which are extended into engagement with the bearings 38 as secured to certain of the beveled side portions of the molding flask 20. By offsetting the arms 55, as 60 at 56, it will be evident, that the same will be permitted to freely receive the molding flask 20 therebetween and should it become necessary, to receive other molding flasks of greater size therebetween.

65 To retain the arms 55 in their lowermost

or normal positions a pivotal catch member 59 is carried upon one of the bearing pillars 43 and is adapted to be moved into engagement with one of the offset portions 56 of the arms 55. As additional means for maintaining the arms 55 in their lowermost positions, supporting arms 60 are secured or formed integral with certain of the sides of the bearing pillars 43 and have formed in their upper extremities squared openings 70 through which wedge members 61 carried upon flexible connections 62 secured to the said pillars as at 63, are passed. It will be readily seen, that the projecting ends of the wedge members 61 will offer efficient stops 80 for the said arms 55, should for any reason the pivotal catch 59 become disengaged therefrom.

Upon the remaining or rear extremity of the carriage 1, other bearing pillars 64 having offset feet 65 formed upon the lower extremities thereof are arranged within suitable seats or recesses formed within the side bars 2, the said offset feet 65 being provided with suitable openings whereby fastening devices 66 may be passed therethrough into engagement with the side bars. Bearing arms 64' are formed integral with the upper portions of the bearing pillars 64 at points adjacent certain of the ends thereof and serve to rotatably support a transversely disposed shaft 67 therebetween. Upon the said shaft 67, at a point substantially intermediate the ends thereof there is formed an enlarged annular portion 68, which portion provides an efficient winding drum for receiving thereabout a cable 69, the purpose of which will be subsequently apparent. As will be noted, one end of the shaft 67 projects beyond its adjacent bearing arm 64' 105 and carries thereon a disk 70, the said extension affording an efficient winding drum whereby a cable 71 may be coiled about the same while the disk 70 serves to prevent lateral displacement of the said cable. A guide member 72 is secured to that bearing pillar 64 as adjacent the extension of the shaft 67 and has rotatably mounted within the longitudinal bore thereof a plurality of idlers 72, whereby, a cables 71 as passing therethrough 110 will be permitted to move freely. Vertically disposed extensions 73 are formed upon the upper portions of the bearing pillars 64 and have formed therein adjacent their respective upper ends bearing openings through 115 which a second transversely disposed shaft 74 is passed. Suitable anti-frictional bearing means may be arranged within the bearing openings formed in the extension 73, not shown. One end of the transverse shaft 74 120 is extended beyond its respective extension 73 and has fixedly mounted thereon a balance wheel 75, the balance wheel in turn being provided with a crank handle 76 to facilitate rotation thereof. Also upon the 130

shaft 74, there is fixedly mounted a gear 77, the said gear being so positioned as to be constantly in mesh with the segmental gear 54 as carried upon the transverse shaft 50. 5 Hence, by rotating the balance wheel 75 through the medium of the crank handle 76, such rotary motion of the gear 77 as will be imparted thereto by reason of its mounting upon the shaft 74 will be transmitted in turn 10 to the segmental gear 54 and as a consequence, the said segmental gear will be rocked upon its respective shaft 50. By rocking the segmental gear 54, a similar movement will be imparted to the arms 55 15 and therefore, the free extremities thereof, that is, those extremities of the same which are engaged with the molding flask 20 will be caused to rise or lower, depending upon the movement of the said segmental gear, 20 thus, raising or lowering of the molding flask 20 in turn. To facilitate movement of the segmental gear 54 in a direction to cause the elevation of the molding flask 20, a contractile coiled spring 78 is engaged 25 with said gear 54, as at 79 and extends diagonally therefrom into engagement with a flooring or shield 80 arranged upon the carriage 1 as at 81. Although it is desirable to provide means whereby downward movement 30 of the segmental gear 54 will be facilitated in order that the arms 55, that is, those ends of the same as engaged with the molding flask 20, may be elevated, it is also desirable to provide for means whereby excessive downward movement of the said segmental gear 54 will be prevented. To this end, I engage with the offset portions 56 of the said arms, a plurality of contractile coiled springs 82, extending the said springs downward 40 into engagement with suitable lugs 83 formed upon the supporting arms 60. By so engaging the contractile springs 82 with the offset portions 56 of the arms 55, when the segmental gear 54 is moved downwardly 45 for a distance to cause proper elevation of the molding flask 20, the same will be placed under a tension sufficient to retard and stop further downward movement of the said segmental gear. A metal rod 84, is engaged 50 with the upper marginal edge of the segmental gear 54 as at 85 and is then bent downwardly upon itself as at 86 and extends to a point in proximity of the rear end of the carriage 1, whereupon a loop 87 55 is formed therein by bending the free end upon itself, in order that the free end of the cable 69 may be passed into engagement therewith. In addition to serving as means for permitting connection of the cable 69 60 with the rod 84, the loop also has engaged therewith a weighted element 88, which weighted element acts in conjunction with the contractile coiled spring 78, to facilitate downward movement of the segmental gear 65 54 and to partly counter-balance the weight

of the molding flask 20 as arranged upon the free ends of the arms 55.

To properly brace the bearing pillars 43 and 64, bars 89 extending longitudinally of the carriage 1 may be and preferably are 70 engaged or formed integral with the adjacent marginal edges of the same and thereby insure the maintaining of the said bearing pillars in rigid spaced apart relation. 75

Other bearing pillars 90 having offset feet 91 formed upon the lower extremities thereof are arranged upon the side bars 2 of the frame 1 adjacent the standards 5 and are secured in position thereupon by means of 80 suitable fastening devices 92 which are passed through apertures formed in the offset feet 91 into engagement with the side bars 2. A shaft 93 is arranged transversely of the carriage 1 and has the ends thereof 85 journaled within the bearing openings as formed in the said bearing pillars 90, one end of the said shaft 93 extending beyond its respective bearing pillar and having fixedly mounted thereon a rearwardly extending arm 94, the free extremity of which is bent or offset as at 95 and is engaged by the free end of the cable 71, the said cable passing through a suitable eyelet 96 carried upon the offset portion 95 and knotted. 90 Laterally extending arms 97 having their free ends bifurcated are fixedly mounted upon the shaft 93 by means of set screws 98 turned into engagement with the same and bearing upon the said shaft. Within the 100 bifurcated free ends of the arms 97, connecting links 99 are pivotally supported and have their lower extremities apertured whereby the fingers 19 carried upon the lower portion of the squared shank 18 may 105 be loosely engaged therewith. By this arrangement, it is to be understood that when the cable 71 is caused to coil about the drum 70 on the transverse shaft 67 upon rotation thereof, the offset extremities 95 of the 110 arms 94 which normally lie in their uppermost positions are caused to move downwardly, and consequently, an upward movement is imparted to the opposite or remaining free ends thereof. Hence, upon the upward movement of the said remaining or free ends of the arms 94, the squared shank 19 will be elevated by reason of its engagement with the connecting links 99. Therefore, the table 16 may be raised and also adjusted to various heights. 115 120

To provide means for governing the movement of the arm 94, there is arranged upon one of the side bars 2 of the carriage 1 adjacent certain of the 125 bearing pillars 43, a diagonally extending arm 100, the base of the arm being offset as at 101 whereby suitable fastening devices may be passed through the same into engagement with the adjacent 130

side bars 12. A series of uniform spaced apart openings 102 are formed within the diagonally extending arm 100 and are adapted to receive therein a stop pin 103, the stop pin being of length to project beyond or to one side of the said arm 100 and to engage the upper marginal edge of the arm 94, whereby to limit the movement of the same. Thus, by varying the positioning of the pin 103 in the various openings 102, the extent of movement of the arm 94 may be accordingly controlled.

Upon the free extremity of one of the arms 55 there is arranged a bearing 104, which bearing is adapted to receive through the transverse bore therein a slidable locking bolt 105 as pivotally engaged to an operating lever 106, the said operating lever in turn, being pivotally mounted as at 107 upon a laterally extending lug 108 also carried upon the said extremity of the said arm 55. A coil spring 109 is engaged with the said bearing 104 and has its remaining end connected to a pin 110 carried upon the slid- 25 able bolt 105. Thus, the said slidable bolt 105 will be normally caused to remain in operative position, that is, in engagement with a suitable keeper 111 as carried upon the adjacent side wall of the molding flask 20. To maintain the slidable bolt 105 out 30 of engagement with its respective keeper 111, a notched extending arm 112 is formed upon a portion of the arm 55 and is adapted to receive therein the free end of the operating lever 166. By engaging the slid- 35 able bolt 105 with the keeper 111 arranged upon the molding flask 20, rotation of the said molding flask when the same is elevated will be prevented and therefore, the pattern 28 or the follower board 21 may be readily and easily removed therefrom.

The operation of my improved molding apparatus may be reviewed as follows:

The table 16 together with the squared shanks are moved to their lowermost positions, consequently, causing the offset extremity of the arm 94 to be moved into its uppermost position and the cable 71 to be partially removed from the drum 70 on the transverse shaft 67. Further, the segmental gear 54 is moved to its uppermost position whereupon, the free ends of the arms 55 will be permitted to swing to their lowermost positions and as a consequence, the molding flask 20 will be permitted to rest fully upon the said table 16. It is to be understood, that the larger end of the molding flask 20 is up, whereby, to permit the slidable plates 25 to be moved inwardly and the pattern together with its flanges 29 arranged over the said open end, the said flanges resting upon the upper faces of the slidable plates 25. The follower board 21 is then filled with sand, whereupon, the same is arranged over the molding flask 20; the pins 30 as carried upon

the flanges 29 projecting through the openings 31 therein and preventing undue lateral movement of the same as well as the pattern 28 with relation to the molding flask. The pivotal catch arms 34 are now swung into engagement with the follower board 21, whereupon, the arms 55 are elevated through the medium of the segmental gear 54 and the gear 77 to permit the turning of the molding flask 20 upon itself and the reversing of the positioning thereof. With the positioning of the molding flask 20 reversed, the smaller end thereof will be arranged upward, thus, permitting the molding sand to be readily poured into the same and tamped. As hereinbefore stated, when the molding flask 20 has been partly filled with the sand, the screen 36 is then inserted therein and the filling of the flask then continued. With the molding flask 20 entirely filled with the sand and the sand tamped, the catch 59 as engaged with one of the offset portions 56 of the arms 55 is disengaged therefrom, thus, permitting the molding flask to be again raised through the medium of the segmental gear 54 and the gear 77. When the molding flask 20 has been raised sufficiently to permit the turning of the same to its first position, the same is then lowered by pulling it downwardly and rotating the shaft 74 carrying the gear 77 in a reverse or counter direction. With the molding flask 20 again lowered, the catch 59 is reengaged with the offset portions 56 of the arm 55. The pin 103 arranged within certain of the openings 102 of the diagonally extending arm 100, whereby to limit the movement of the arm 94, in order that vertical movement of the table 16 will be controlled. The catch 59 is again disengaged from the offset portion 56 of the arm 55 and the slidable bolt 105 is engaged with its respective keeper 111 carried by the molding flask. The molding flask is now elevated for a slight distance by means of the arms 55 and the catch arms 34 are disengaged from the follower board 21. Thereby, permitting the same to be withdrawn or removed from the molding flask. Upon removal of the follower board 21, the flanges 29 as carried upon the pattern 28 will drop into engagement with the guide elements or pins 15 and upon further elevation of the molding flask, the said pattern being disengaged from the sand mold may be readily removed. Upon removal of the pattern 28 from engagement with the sand, the finger 37 as carried thereby will cause the formation of a vertically disposed channel through the sand mold, the said channel communicating with the form therein, in order that the molten metal may be poured into the same. With the follower board 21 removed from the molding flask 20, the pin 103 is disengaged from the particular opening within the arm 100 and the molding flask 20 is

again lowered onto the said table 16. At this time, the sides of the molding flask are tapped by the hammers 41 as carried thereby to cause the sand mold to be disengaged 5 from the side walls thereof. With the sand mold free or loosened, the flask 20 is released, whereupon, the arms 55 will be caused to instantly rise, by reason of the contractile spring 78 and the weight 88 as 10 engaged with the segmental gear 54. Simultaneous with the raising of the flask 20, the table 16 will be caused to lower by reason of the weight of the sand mold thereon. Such lowering of the table 16 will cause the 15 arm 94 to be rocked by reason of its engagement with the shaft 93, thereby withdrawing or uncoiling the cable 71 from about the extension of the shaft 67, rotating the said shaft, whereupon, the cable 69 as engaged 20 with the winding drum 68 will be coiled thereabout and the segmental gear 54 as engaged by the free end of the said cable 69 is moved into its lowermost position. With the parts of the apparatus so positioned, the 25 sand mold may be readily removed from the table 16 and the forming of the second sand mold, whereby to complete the casting, then carried on. When it is desired to again elevate the table 16 and lower the flask 20, the 30 said flask may be drawn downwardly or if the same is of material weight, the balance wheel 75 may be rotated in a counter direction by means of the crank handle 76, thus, causing the segmental gear 54 and the arm 35 94 to assume their normal positions. Obviously, the contractile coiled spring 82 will prevent the segmental gear 54 from moving downwardly too far.

By arranging my improved molding apparatus upon the carriage 1, it will be understood that the same may be readily ported from place to place, during the molding process, thereby, obviating the necessity of handling the heavy and cumbersome elements of the said apparatus or the handling 45 of the molded article.

Should the table 16 not be of a size to properly support the molding flask 20, the same may be readily removed from the lateral supporting arms 8 and a second table 50 of suitable size substituted in lieu thereof.

Should it become necessary to use my improved molding apparatus in the forming of molds of greater size, the slideable journal boxes arranged upon the reduced extensions 55 46 of the bearing pillars 43 may be adjusted to raise the shaft as mounted therebetween through the medium of the set screws 48. By varying the positioning of the said shaft, 60 the arms 55 will as a consequence, be also raised with relation to the table 16, thereby, allowing proper engagement of the larger molds when placed upon the said table 16 within their respective flasks.

65 As many changes could be made in the

above construction and many apparently widely different embodiments of this invention could be made without departing from the scope thereof, it is intended that all matter contained in the above description or 70 shown in the accompanying drawings shall, as hereinbefore stated, be interpreted as illustrative and not in a limiting sense. It is also to be understood that the language used in the following claims is intended to 75 cover all of the generic and specific features of the invention herein described and all statement of the scope of the invention, which, as a matter of language might be said to fall therebetween.

Having described my invention, what I claim as new and desire to secure by Letters Patent, is:

1. In molding apparatus, a supporting table, flask supporting means, means for moving said table, other means for moving said flask supporting means, and means for independently or collectively operating said moving means.

2. In molding apparatus, a supporting 90 table, a flask, means for pivotally supporting and moving said flask vertically, means for moving said supporting table vertically, and other means engaged with said flask and table moving means for operating the same 95 collectively.

3. In molding apparatus, a supporting table, a flask, means for pivotally supporting and moving said flask vertically, means for moving the supporting table vertically, 100 and other means engaged with said flask and table moving means for operating the same independently or collectively.

4. In molding apparatus, a supporting frame, standards arranged upon said supporting frame, a table carried by said standards and vertically adjustable with relation thereto, a flask, means engageable with the flask for pivotally supporting the same and moving the same vertically, and means on 110 the frame connected to said table and flask supporting means for operating the same independently or collectively.

5. In molding apparatus, a supporting frame, standards arranged upon said frame, 115 laterally adjustable carriages supported on portions of said standards, a table removably engaged with said carriages and being vertically adjustable with relation to the standards, flask supporting means, and means on the frame connected to the table and flask supporting means for moving the same independently or collectively.

6. In molding apparatus, a supporting frame, standards arranged upon said frame, 125 laterally adjustable carriages supported on portions of the standards, a table removably arranged on said carriages, said table being adjustable vertically with relation to the standards, a flask, means for pivotally sup- 130

- porting and moving said flask vertically, and means on the frame connected to said table and flask moving means for operating the same independently or collectively.
- 5 7. In molding apparatus, a supporting frame, supported by said supporting frame, laterally adjustable carriages arranged on portions of the standards, a table removably engaged with said carriages, said table being adjustable vertically with relation to the standards, a flask, means for pivotally supporting and moving said flask vertically, and means on the frame for operating the table and flask moving means collectively.
- 10 8. In molding apparatus, a supporting frame, a table mounted for vertical movement upon said frame, a flask, means for pivotally supporting and moving said flask vertically, means engaged with said table and said flask moving means for operating the latter upon movement of the former, and means engageable with said table and flask moving and engaging means for controlling movement thereof.
- 15 9. In molding apparatus, a supporting frame, standards on said supporting frame, laterally adjustable carriages supported on portions of said standards, a table removably engaged with said carriages, said table being adapted to move vertically with relation to the standards, a rock arm engaged with the table and extending longitudinally of the supporting frame, a flask, means for pivotally supporting and moving said flask vertically, operating means arranged in spaced relation to said standards, flexible connections engaged with the ends of said rock arm and flask moving means and the operating means, said operating means being actuated upon vertical movement of the supporting table to collectively move the flask supporting and moving means vertically.
- 20 10. In molding apparatus, a supporting frame, standards carried by said supporting frame, carriages slidably supported by portions of said standards, a table removably engaged with said carriages, said table being adapted to move vertically with relation to the standards, a rock arm mounted on the frame and engaged with the vertically movable table, means for pivotally supporting and moving a flask vertically, operating means on the frame in spaced relation to said flask and table, means for connecting the rock arm and the flask supporting and moving means to said operating means, said flask supporting and moving means being moved vertically upon movement of the table, and means engageable with said rock arm for limiting movement thereof to permit independent moving of the last supporting and moving means.
- 25 11. In molding apparatus, a supporting frame, a vertically movable supporting ta-
- ble on said supporting frame, vertically movable flask supporting means, a plurality of pairs of spaced apart bearing pillars on the frame, a shaft mounted between certain of the pairs of said bearing pillars, means arranged on said shaft and engaged with said flask supporting means for imparting movement thereto, a second shaft mounted between certain of the remaining pairs of bearing pillars, a rock arm mounted on said second shaft and extending longitudinally of the supporting frame, means carried on one extremity of the rock arm engaged with the vertically movable table, another shaft mounted between the remaining bearing pillars, and means arranged on said third shaft and connected to the flask moving means and to the rock arm, said flask moving means being actuated upon movement of the vertically movable table and the rock arm, and means engageable with said rock arm for preventing movement of the same to permit independent movement of the flask supporting means.
- 30 12. In molding apparatus, a supporting frame, standards arranged on said supporting frame, a plurality of carriages slidably supported by portions of the standards, a supporting table removably arranged upon the slidable carriages, said supporting table being adjustable vertically with relation to the standards, a plurality of pairs of bearing pillars arranged on the supporting frame, journal boxes adjustably mounted upon certain of the pairs on said bearing pillars, a shaft mounted in said journal boxes, power transmitting means mounted on said shaft, flask supporting and moving means engaged and carried by said power transmitting means, a transverse shaft journaled in certain other of the pairs of said bearing pillars, a rock shaft mounted on said transverse shaft, means engaged with one extremity of the rock shaft for connecting the same with said vertically movable table, another shaft mounted between the remaining pairs of bearing pillars, gearing on the said last shaft engaged with the power transmitting means and adapted to move and be moved by the same, means for connecting one end of the rock arm to said gearing, the gearing being rotated upon vertical movement of the movable table whereby to actuate the flask supporting means, and means on the same engageable with said rock arm for limiting movement thereof to permit movement of the flask supporting means independently of the same.
- 35 13. In molding apparatus, a supporting frame, standards arranged upon said supporting frame, a plurality of carriages slidably supported by portions of the standards, a supporting table removably arranged upon the slidable carriages, said supporting table being adapted to move vertically with rela-

- tion to the standards, a plurality of pairs of bearing pillars arranged on the supporting frame, a shaft adjustably mounted between certain of the pairs of said bearing pillars, 5 power transmitting means carried by the shaft, flask supporting and moving means engaged with a power transmitting means, said flask supporting and moving means being adapted to pivotally support a flask, a 10 second shaft journaled between the remaining bearing pillars, gearing on said second shaft engaged with the power transmitting means, means connected to the vertically movable table and the gearing for imparting motion thereto upon movement of said table, 15 means carried by the same and engageable with said connecting means for permitting independent movement of said gearing, and means on the flask supporting and moving means engageable with the same for preventing pivotal movement thereof when raised.

In testimony whereof, I affix my signature hereto.

MEINDERD S. NAP.
